UNDERCUTTING EARTH AUGER

Ralph A. Ransdall, San Francisco, Calif.

Application October 31, 1949, Serial No. 124,680

8 Claims. (Cl. 255—74)

1

My invention relates to means for providing or boring holes in material especially earth and is concerned largely with an earth auger, usually power driven, effective to provide an enlarged chamber or cavity at the bottom of or adjacent the bottom of a cylindrical hole previously bored in the ground.

In driving foundation holes it is advisable to provide a mechanism effective to bore a circular cylindrical hole along an axis extending into the ground. In addition to this, in order to secure an appropriate anchorage for towers, supporting structures or the like disposed in the bored holes, it is advisable to enlarge the bottom of the bore so that concrete or other placement material will have a secure interengagement with the earth and will provide a firm support and foundation for the structure.

It is therefore an object of my invention to provide an earth auger effective to undercut adjacent the bottom of a bored hole to provide a chamber.

Another object of my invention is to provide an undercutting earth auger automatically effective adjacent the bottom of the hole to provide an enlarged chamber.

A further object of my invention is to provide an undercutting earth auger easily introduced into a hole previously bored by a suitable tool and as easily withdrawn from the bore after the undercutting has been accomplished.

A still further object of my invention is to provide an undercutting earth auger useful with the power driving mechanisms generally available.

A still further object of my invention is to provide means for driving the cutting device in an undercutting earth auger at various distances from the rotational axis without undue strain on the driving and setting mechanisms.

An additional object of my invention is in general to provide an improved undercutting earth auger.

These objects of the invention as well as others are attained in the embodiment described in the accompanying description and illustrated in the accompanying drawings in which

Figure 1 is a cross-section of a circular cylindrical earth bore showing in side elevation my earth auger therein.

Figure 2 is a view comparable to Figure 1, but showing the cutters in an extended position.

Figure 3 is a plan of the structure shown in Figures 1 and 2, a part of the driving shaft being disclosed in cross section and a part of the figure being broken away to reduce its size.

Figure 4 is a cross-section the plane of which is indicated by the line 4—4 of Figure 3.

Figure 5 is a detailed side elevation of the structure shown in Figure 4 but with parts of

2

the centrally located mechanism broken away to disclose the interior construction, particularly the teeth.

Figure 6 is a cross-section the plane of which is indicated by a line 6—6 of Figure 4.

Figure 7 is a cross-section the planes of which are indicated by the lines 7—7 of Figure 4.

Figure 8 is a fragmentary cross-section on an axial plane showing the detailed arrangement of a packing mechanism.

While the earth auger of my invention can be made in a number of different ways depending upon the particular duty for which it is especially designed and depending also upon the environment in which it is utilized, it has successfully been incorporated in the form shown herein. Customarily, a standard form of earth auger is first used to provide a bore 6 in the earth 7, the bore having a uniform, circular cylindrical cross-section. In the beginning of the undercutting operation, my undercutting earth auger is disposed in a position approximately as illustrated in Figure 1. The mechanism is located within the bore 6 coaxially with the axis 8 of a driving shaft 9 extending from a suitable source of rotation or driving power, not shown, usually located at or above the surface of the earth 7. The shaft 9 is preferably square in cross-section and at its lower end is provided with a circular portion 11 fitting within a sleeve 12 forming part of a driving tube 13. Also included in the driving tube 13 is a pilot sleeve 14 surrounding the short end of the shaft. The interengagement between the tube 13 and the shaft 9 is further effectuated by a cross pin 16 through the sleeve 12 so that the shaft 9 and the tube 13 partake of rotational movement and of axial translation in unison.

At the bottom, the driving tube 13 ends in a flange 17 receiving fasteners 18 for securing the driving tube to a crosshead 19. The crosshead is a rather massive block-like structure disposed symmetrically with respect to the axis 8 and includes a central web 20, a top plate 21 and a bottom plate 22. These are closed at the sides by removable closure plates 23 and 24 held on by fasteners 26. The web 20, the top and bottom plates 21 and 22 and the closure plates 23 and 24 together define a pair of transversely extending channels 21 and 28 respectively (see Figures 6 and 7). Each of these channels is rectangular or preferably square in transverse cross-section and each of them is arranged so that its central axis 29 or 31 is horizontal. The axes 29 and 31 are parallel to each other and are approximately radial with respect to the axis 8 although they are spaced so that the axis 8 extends between them. The axes 29 and 31 are likewise both contained in a plane normal or perpendicular to the rotational and translational axis 8.

Both of the channels 27 and 28 extend crosswise from one end of the crosshead to the other.

Since the mechanisms disposed in the channels 27 and 28 are identical in most respects a description of one of them applies equally to the other. In the channel 27, for example, there is disposed a cutter carrier 33 and in the channel 28 there is disposed a cutter carrier 34. The cutter carrier 34 includes a bar of generally rectangular or square cross-section freely slideable within the channel 28 and at its outer end provided with an extension 36 (Figure 7) conveniently welded thereto and extending through an opening 37 in the bottom plate 22 of the crosshead. Removably secured to the extension 36 by appropriate fasteners 38 is a cutter 39. This is of any suitable sort for working in earth or comparable material and preferably includes a beveled plate carrying a hard facing material.

The cutter carrier 33 is similarly provided with a cutter 41 of a type usually comparable to that of the cutter 39 although the two cutters may have differences between themselves. Both cutter carriers are freely slideable within their channels.

It is intended that the cutter carriers be moved equally and simultaneously in radially opposite directions, either so that they can both be retracted together or so that they both can be extended together. For this reason the cutter carrier 33, for example, is provided on an interior face with a group of series of rack teeth 42, the teeth being disposed at a predetermined or selected direction of inclination. Comparably, the cutter carrier 34 is provided with a group or series of rack teeth 43 but the inclination of these teeth is oppositely disposed to that of the teeth 42 as especially shown in Figure 5, for example.

Adapted to mesh with the teeth 42 and 43 are correspondingly inclined teeth 44 and 45 on a plunger 46 disposed coaxially with the driving tube 13 and extending into and designed to slide through the crosshead 19. With this arrangement, translational movement of the plunger provides corresponding and oppositely directed radial movement of the cutter carriers 33 and 34. The plunger preferably is rectangular in cross-section and in addition to its other support is guided for translational movement by a guide tube 49 forming part of and extending from the lower plate 22 of the crosshead. Not all of the plunger 46 is provided with teeth. The remaining portion is smooth or plain and a packing mechanism 51 (see Figure 8) is provided to ensure that earth and other deleterious material is kept out of the sliding inter-connection. The packing 51 is renewable by removal of a securing plate 52 normally held in position by a screw 53. Since the plunger 46 is square, there are four packing structures 51 provided, one on each side.

Normally, it is desired to keep the cutter carriers retracted so that I provide a means for this purpose. Conveniently that means takes the form of an elongated coil spring 54 disposed within the hollow interior of the plunger 46. The spring at its upper end abuts a nut 56 on a guide rod 57 extending within the spring and likewise extending to a plate 58 pressed against a shoulder at the lower end of the drive member 12 where it merges with the driving tube 13. The lower end of the spring 54 rests at the bottom of the recess within the plunger so that the plunger is urged to project from the guide tube 49. The inclination of the teeth 44 and 45 being appro-

priate, the cutter carriers are in this fashion retracted firmly against adjustable stop screws 59 at opposite ends of the crosshead, the screws being retained in adjusted position by appropriate nuts 61. The structure is held to an adjustable minimum envelope diameter when the cutters are withdrawn.

While the cutters are normally retracted as the mechanism is introduced into the bore 6, it is desired automatically to extend such cutters when the bottom of the bore has been reached. For that reason I provide at the lower end of the plunger 46 an abutment plate 62 mounted for rotation relative to the plunger. Since the plunger itself is rotatable about an axis and since the abutment plate 62 is rotatable with respect to the plunger it is feasible to hold the abutment plate stationarily against the earth 7 while the remaining part of the structure revolves. The abutment plate 62 is mounted on an anti-friction bearing 63 appropriately retained at the bottom of the plunger 46. An effective earth seal 64 prevents the entry of foreign matter to the bearing. A centering and guarding cone tip 66 not only forms an appropriate housing for the bearing but likewise assists in centering the structure in the bore 6.

When the mechanism is lowered into the bore and the weight of it comes upon the plate 62 as the plate engages the subjacent earth 7, the plunger is driven into the crosshead, or considered oppositely, the crosshead descends to telescope the plunger into the guide 49. This relative movement of translation projects both of the cutter carriers 33 and 34 to their maximum extent. Since this action of projecting the cutter carriers can occur and usually does occur progressively as the crosshead is lowered, the cutters extend radially outward at an inclination to the axis 8 depending upon the inclination of the driving teeth, 44 and 45, especially as illustrated in Figure 2. As the cutters descend, the diameter of the excavated hole is enlarged and the remainder of the earth is undercut. The sleeve 49 covers more and more of the plunger 46 until the bottom of the stroke has been reached. At that time the weight of the mechanism is removed from bearing upon the plunger and the plate 62 and the spring 54 is then effective during the upward movement of the crosshead to project the plunger from the guide tube 49 or, considered conversely, to lift the crosshead from the plunger. Due to the inclination of the driving teeth 44 and 45, the two cutter carriers are retracted to their original position having an envelope diameter not greater than that of the bore 6. In this fashion the undercut is made and the auger is withdrawn.

Since the cutter carriers are relatively close fits within their channels, I provide a means for preventing the entrapment of air or of foreign material within the channels 27 and 28. Lubricant is also present in contact with these parts and tends to displace as they are moved. For these reasons, as especially shown in Figure 6, each of the channels is provided with a conduit 71 leading to a cross bore 72. The cross bore merges with passages 73 extending through the upper plate 21 to the interior of the drive tube 13 so that communication is established between them and with the drive tube 13 atmosphere. Lubricant and air can consequently interflow freely as the cutter carriers retract and project, so that excess pressures or partial vacuums cannot occur. Disposed on the upper surface of the crosshead are appropriate hand grips 74 so

that the tool can be manipulated readily, can be started in position and can be manually rotated while it is being adjusted initially or retracted finally from the earth.

I claim:

1. An undercutting earth auger for use in a hole having a central axis comprising a cross-head, means for supporting said crosshead for rotation about said axis, a cutter carrier, means for supporting said cutter carrier in said cross-head for movement approximately radially of said axis, a cutter on said cutter carrier, means for urging said cutter carrier toward said axis, and earth engaging plunger mounted in and depending from said crosshead for movement along said axis, and means interconnecting said plunger and said cutter carrier for moving said cutter carrier away from said axis upon upward movement of said plunger along said axis.

2. An undercutting earth auger for use in a hole having a central axis comprising a cross-head, means for supporting said crosshead for rotation about said axis, a cutter carrier, means for supporting said cutter carrier in said cross-head for movement approximately radially of said axis, a cutter supported on said carrier, inclined rack teeth formed on said cutter carrier, an earth engaging plunger mounted in and depending from said crosshead for movement along said axis, inclined rack teeth on said plunger meshing with the inclined rack teeth on said cutter carrier, and a spring effective to project said plunger downwardly along said axis and through said meshing teeth to retract said cutter carrier toward said axis.

3. An undercutting earth auger for use in a hole having a central axis comprising a cross-head, means for supporting said crosshead for rotation about said axis, a pair of cutter carriers, means for supporting said cutter carriers in said crosshead for movement approximately radially of said axis, cutters supported on said cutter carriers, inclined rack teeth formed on said carriers, an earth engaging plunger mounted in and depending from said crosshead for movement along said axis, oppositely inclined rack teeth on said plunger meshing with the respective inclined rack teeth on said cutter carriers, and a spring effective to project said plunger downwardly along said axis and simultaneously to retract both of said cutter carriers toward said axis.

4. An undercutting earth auger for use in a hole having a central axis comprising a cross-head, means for supporting said crosshead for rotation about said axis, a pair of cutter carriers, means for supporting said cutter carriers in said crosshead for movement approximately radially of said axis, cutters on said cutter carriers, a plunger mounted in said crosshead for movement in both directions along said axis, means interconnecting said plunger and said cutter carriers for simultaneous positive movement in both directions with respect to said crosshead, and an earth engaging abutment plate mounted for rotation on the lower end of said plunger.

5. An undercutting earth auger for use in a hole having a central axis comprising a cross-head, means for supporting said crosshead for rotation about said axis, said crosshead having a channel therein arranged with the channel axis spaced from said rotational axis and in a plane normal thereto, a cutter carrier movable in said channel, a cutter on said cutter carrier, inclined rack teeth on said cutter carrier, a plunger

mounted in said crosshead for movement along said axis, meshing rack teeth on said plunger, and means for moving said plunger along said axis and through said meshing teeth for moving said cutter carrier in said channel.

6. An undercutting earth auger for use in a hole having a central axis comprising a cross-head having a pair of parallel channels therein, a pair of cutter carriers slideable in said channels, means for rotating said crosshead about said axis between said channels, a plunger mounted in said crosshead for movement along said axis, meshing rack teeth on said plunger and on said cutter carriers for imparting simultaneous sliding movement to said cutter carriers as said plunger moves along said axis, an earth engaging abutment plate rotatably mounted on one end of said plunger for use in moving said plunger in one direction, and a spring interposed between said crosshead and said plunger for urging said plunger in an opposite direction.

7. An undercutting earth auger for use in a hole having a central axis comprising a driving shaft adapted to be rotated about said axis, a crosshead, a driving tube on said crosshead and engaging said shaft, a guide tube on said cross-head, said tubes being disposed along said axis, a pair of cutter carriers means mounting said cutter carriers in said crosshead for approximately radial sliding movement on opposite sides of said axis, cutters on said cutter carriers, a plunger slidably mounted within and projectable from said guide tube, means interconnecting said cutter carriers with said plunger for sliding movement in opposite directions as said plunger slides within said guide tube, and a spring for urging said plunger into a position projecting from said guide tube.

8. An undercutting earth auger for use in a hole having a central axis comprising a driving shaft adapted to be rotated about said axis, a crosshead, a driving tube on said crosshead and engaging said shaft, a guide tube on said cross-head, said tubes being disposed along said axis, said crosshead having a pair of channels square in cross section and extending approximately radially of and on opposite sides of said axis, a pair of cutter carriers square in cross section and slidably disposed in said channels, inclined rack teeth on said cutter carriers, a plunger slideable in and projectable from said guide tube along said axis, oppositely inclined rack teeth on said plunger respectively engaging said teeth on said cutter carriers, an earth engaging abutment plate rotatably mounted on one end of said plunger for use in moving said plunger into said guide tube, and a spring engaging said plunger for urging said plunger into a position projecting from said guide tube.
